R. F. BOYD.
NON-REFILLABLE BOTTLE.
APPLICATION FILED FEB. 26, 1917.
1,289,373.

Patented Dec. 31, 1918.

UNITED STATES PATENT OFFICE.

ROY F. BOYD, OF VENICE, ILLINOIS.

NON-REFILLABLE BOTTLE.

1,289,373.

Specification of Letters Patent. Patented Dec. 31, 1918.

Application filed February 26, 1917. Serial No. 151,000.

To all whom it may concern:

Be it known that I, Roy F. Boyd, a citizen of the United States, residing at Venice, in the county of Madison, State of Illinois, have invented certain new and useful Improvements in Non-Refillable Bottles; and I do hereby declare the following to be a full, clear, and exact description of the invention, such as will enable others skilled in the art to which it appertains to make and use the same.

This invention relates to non-refillable bottles.

The object of this invention is to improve the construction of non-refillable bottles in such a manner that a practical valve mechanism will be provided which, while permitting the liquid to be poured from the bottle will be properly constructed to prevent the bottle from being refilled, even by the well-known tricks with which so-called non-refillable bottles have been heretofore fraudulently manipulated in order to fill the bottles in spite of the valve mechanisms with which they have been provided.

With the above objects in view and such others as may hereinafter appear, my invention will now be fully set forth and described, reference being had to the accompanying drawing:

In the drawings:

Figure 1 is a vertical section through the non-refillable mechanism,

Fig. 2 is a side elevation of a stopper device,

Fig. 3 is a section on line 3-3 of Fig. 1,

Fig. 4 is a section on line 4-4 of Fig. 1, and

Fig. 5 is a vertical section taken on line 40 5-5 of Fig. 1.

Referring more particularly to the drawings, 1 represents a bottle structure which has a straight cylindrical neck 2. Preferably adjacent that point where the neck 2 joins the shoulder of the bottle 1, the neck is internally provided with an annular offset 3 which forms an inclined or conical seat 4. The seat 4 receives an inverted conical valve or plug 5 of glass or other magnetically non-conductive material, said valve 5 at its base or upper end being just sufficiently smaller than the internal diameter of the neck to permit it to unseat when the bottle is inverted. At a suitable intermediate distance between the seat 4 and the mouth of the neck, the latter is internally

provided with the opposite notches or recesses 6, which are adapted to be engaged by suitable locking devices as will later appear. Fitted within the neck, and extending almost to the valve 5, is a stopper 7 which I prefer to make a clear glass, the stopper 7 having its lower face slightly rounded in opposition to the convex upper face of the valve 5, so that when the valve 65 and stopper come into contact, a slight rocking action may occur therebetween. Passing diametrically through the stopper 7 is a tubular opening 8 which terminates at its extremities into lock notches 10 which are 70 adapted to coöperate or coincide with the lock notches 6 in the neck of the bottle when the stopper is seated therein, the notches 10 and 6 together providing recesses for the reception of the keys 11 which, when the 75 stopper is seated in position, are held in locking position, by means of the coil spring 12 which projects through the passage 8. Obviously, the notches 10 must be of sufficient depth to contain the keys 11 until the 80 notches 10 have come into full coincidence with the notches 6.

In order to permit the passage of liquid from the bottle, the stopper 7 is provided with the zig-zag or tortuous ports 13 which 85 are preferably two in number, and are distorted in opposite directions, and furthermore lie upon opposite sides of the passage 8. By the provision of the two ports 13, liquid may be poured from one, while air is 90 admitted to the bottle through the other. In order to properly protect the contents of the bottle against leakage and other loss until sold, the plugs 14 are inserted in the upper ends of the ports 13 and are therein 95 sealed by means of wax or any other suitable material which will not prevent their ready removal.

The assemblage of my improved bottle structure is apparent from the foregoing 100 description. In its operation, the plugs 14 are first removed and the bottle then inverted in a position to permit air to enter one port 13 while the contents may pass out of the other. The valve 5 then tips off of 105 the seat 4 until its upper rounded surface abuts against the rounded lower end of the stopper 7, this locking relation of the valve and stopper giving a maximum clearance for the outpouring of the liquid, while causing the valve or plug 5 to immediately drop back on its seat as soon as the bottle has

reached such a position where it might be possible to cause liquid to leak therein. The zig-zag or tortuous relation of the ports 13 prevents the insertion of any implement, such as a wire by means of which the valve 5 may be manipulated, and the construction of the valve of material which is magnetically non-conductive prevents the lifting of the latter by means of a magnet. Furthermore, the space between the valve 5 and the bottom of the stopper is such that together with the rounded surface of the tube, it is impossible to wedge the valve in any way so that it cannot fall back upon its seat.

15 What I claim as my invention is:—

The combination with a bottle neck, hav-

ing an annular valve seat in its inner end, of a substantially conical valve engageable on the seat and having a convex upper surface, a stopper cylinder in the bottle neck 20 loosely confining the valve and having a convex lower face opposing the convex face of the valve, and means for locking the stopper cylinder in the bottle neck, said cylinder being provided with ports extending 25 longitudinally therethrough.

In testimony whereof, I affix my signature, in the presence of two witnesses.

ROY F. BOYD.

Witnesses:

MAY STARR,
CARL L. BOYD.
